(57) **CLAIM**

The ornamental design for a sound amplification ear device with ear phone, as shown and described.

DESCRIPTION

FIG. 1 is a top perspective view of a sound amplification ear device with ear phone showing my new design;
 FIG. 2 is a bottom perspective view thereof;
 FIG. 3 is a first side elevation view thereof;
 FIG. 4 is a second side elevation view thereof;
 FIG. 5 is a top plan view thereof;
 FIG. 6 is a bottom plan view thereof;
 FIG. 7 is a rear elevation view thereof; and,
 FIG. 8 is a front side elevation view thereof.
 The broken lines form no part of the claimed design.
